UNITED STATES PATENT OFFICE

PETER SIVERTSEN, OF NEW YORK, N. Y.

CLEANING DEVICE FOR SLICING-MACHINE KNIVES

Application filed January 4, 1926. Serial No. 79,174.

This invention relates to cleaning devices and has more special reference to a device for cleaning the knives of slicing machines.

Comprehensively stated, the invention consists of a scraper adapted to engage the rotary knife of a slicing machine and a receptacle for receiving the material removed from the knife by the scraper.

The object of the invention is to provide a comparatively simple structure which can be quickly removed from the slicing machine and which will effectually free the knife of accumulated waste.

While one embodiment of the invention is disclosed in the accompanying drawing it is to be understood that this embodiment merely serves as an illustration of the underlying principles of the invention so that they may be readily comprehended by those skilled in the art and are not intended as limiting the invention to the specific form disclosed therein.

In said drawing:

Fig. 1 is an elevation of the invention used in conjunction with a rotating knife,

Fig. 2 is an end elevation of Fig. 1, and is shown partly fragmentary and partly in section,

Fig. 3 is a section of Fig. 1 on the line 3—3, and

Fig. 4 is a section of Fig. 2 on the line 4—4.

Continuing now by way of a more detailed description, a waste receptacle A is preferably formed from sheet metal and is bent in the manner shown more particularly in Fig. 3, one face of the receptacle being extended at F to provide adequate support for the receptacle in the manner to be described. The lower end of the extension piece is cut away at A'' to receive the foot B of a supporting bracket or angle iron, the foot B being secured to the slicing machine by screws C or other equivalent means. The vertical edge of the wall D which is brought back in the bending operation to a position near the extension piece F is left free although, of course, the edge might, if desired, be secured to the front wall of the receptacle A although the free arrangement is preferred as permitting the receptacle to be freed of accumulated

waste by separating the parts and bending back the wall D. In order to keep the wall D in place, the upstanding portion or post E of the angle iron is arranged to abut against the wall D and the extended portion F of the receptacle A. The upper edge of the receptacle A is extended to form an inclined wing G to afford a mounting block H which is secured to the wing G by screw G'. One end of this block is bevelled at J to form a socket K adjacent to the wing G to receive one edge of the scraper L, the bevel serving to provide sufficient clearance so that the scraper may be flexed in the socket to effectively bear on the knife N to be cleaned. The scraper blade preferably consists of somewhat flexible material and is pressed against the knife N by a plurality of screws K, the latter being spaced from the portion of the socket seating one edge of the scraping blade so that a slight leverage will be afforded to exert the requisite pressure on the knife N.

It is claimed:

1. A cleaning device for slicing machines combining a receptacle having an extended portion, a free end located contiguous to the extended portion and a supporting post adjacent to the free end and extended portion.

2. A cleaning device for a slicing machine comprising a block having a recess, a scraper blade having one edge resting in the recess and means to tilt the blade about the edge resting in the recess.

3. A cleaning device for slicing machines, combining a support, a scraper adjustably secured to the support, and a receptacle located below the scraper in such a position that material removed by the scraper will fall into the receptacle, and having the support attached to its upper end.

4. A cleaning device for slicing machines, combining a support, having a recess, a scraper tiltably mounted in said recess, means for adjusting said scraper, and a receptacle located below the scraper in such position that the material removed by the scraper will fall into the receptacle and having the scraper support attached to it.

5. A cleaning device for slicing machines combining a block having a recess, a scraper

comprising a flat plate having one edge fulcrumed in the recess, and means to tilt the scraper relatively to the block about the fulcrum edge.

5 Signed at the city of New York in the county of New York, and State of New York, this 19th day of November, 1925.

PETER SIVERTSEN.
